B. Marker Clark 400p⁵

UNITED STATES PATENT OFFICE.

FRANK TINKER, OF SUTTON COLDFIELD, ENGLAND.

PRODUCTION OF PETROL.

Application filed September 25, 1922, Serial No. 590,480, and in Great Britain January 7, 1922.

This invention relates to the production of petrol and like motor spirits from heavy hydrocarbon oils such as crude mineral oils, tar oils, fuel oils, kerosene and the like, and has for its object to enable a higher yield of motor spirit to be obtained economically from a system containing, for example, the elements of an ordinary "topping" plant. Such a plant consists essentially of a fire-heated pipe still, a separating drum, a fractionating column and a condenser, all connected in series by suitably arranged pipes.

According to the present invention the liquefied portion of the distillate collected by reflux in the fractionating column is passed through an additional still and superheater wherein such distillate is cracked, and the resultant vapour cracked is delivered to the fractionating column or to any other suitable part of the system.

The accompanying diagram illustrates one manner of carrying the invention into effect.

Referring to the diagram *a* is the fire heated pipe still, *b* the separating drum, *c* the fractionating column, and *d* the condenser of an ordinary topping plant. In conjunction with this apparatus there may be employed a heat interchanger *e*, whereby heat contained in the hot residue drawn from the separating drum *b* may be utilized for initial heating of the crude oil passing to the still *a*.

In carrying my invention into effect I add to the above mentioned system what may be termed a loop or closed circuit *f* commencing at the fractionating column *c* and after passing through another still *g* and superheater *h* returning to the fractionating column *c*. Liquid distillate drawn from this column *c* is passed through the said still *g* and superheater *h* and is cracked therein and the resulting cracked vapour is delivered to the same fractionating column. In this way the normal yield of petrol can be advantageously increased in an economical manner and without inconvenient change of existing plant. Furthermore, relatively clean distillate of a more or less constant grade, and free from light oil on the one hand and heavy residue on the other, is supplied to the superheating system for cracking purposes.

It is not necessary to return the vapour

from the extra still *g* and superheater *h* to the fractionating column *c*, as it may be delivered to any other suitable part of the main system, e. g. the separating drum *b* as indicated by dotted lines in the diagram. Likewise, if in certain circumstances it be desired, the pipe still and separating drum of the topping plant may be replaced by the older form of crude still, in which case the vapour from the additional parts *g* and *h* could be returned to the still.

The extra still *g* and superheater *h* may consist of two separate parts, or a single element may perform the double function of the two parts.

When using a loop in accordance with this invention for increasing the yield of petrol from an ordinary topping plant it is possible to effect the cracking of oil in the loop under very advantageous conditions for the reason that the volume of flow per unit of time through the loop can be much greater than in the main part of the system and consequently carbonization can be reduced to a minimum. Owing to the greater volume of vapour and consequently heat delivered into the fractionating column when the loop is employed, it is necessary to increase the provisions ordinarily made in conjunction with that column for cooling the vapour, and this can be effected in any convenient manner.

Having thus described my invention what I claim as new and desire to secure by Letters Patent is:—

1. A method of treating oil which comprises distilling the oil to top the same, fractionating the vapors formed to form a condensate while out of contact with raw oil and treating the condensate thus formed to crack the same and thus to form a cracked vapor, introducing said cracked vapor directly into the first mentioned vapors.

2. The process of treating oil which comprises distilling the oil to top the same in a distilling zone, refluxing vapors thus formed to form a reflux condensate while out of contact with raw oil, cracking the reflux condensate in a separate zone to form a cracked vapor and introducing said cracked vapor directly into the first mentioned vapors, undergoing said reflux condensation.

3. Apparatus for treating oil, comprising means, means for superheating vapors means for vaporizing said oil, a rectifying formed in said second vaporizing means, means, means for passing vapors formed in means for passing said superheated vapors to said vaporizing means to said rectifying directly to said rectifying means. means, a second vaporizing means, means In testimony whereof I have signed my for passing condensate formed in said rectifying means to this specification.

FRANK TINKER.
